UNITED STATES PATENT OFFICE.

WILLIAM P. ANDERSON AND LOUIS H. NOLTE, OF CINCINNATI, OHIO, ASSIGNEES TO FERRO-CONCRETE CONSTRUCTION COMPANY, OF CINCINNATI, OHIO, A CORPORATION OF OHIO.

REINFORCED CONCRETE FLOORING.

No. 875,975.

Specification of Letters Patent.

Patented Jan. 7, 1908.

Application filed January 2, 1906. Serial No. 294,065.

To all whom it may concern:

Be it known that we, WILLIAM P. ANDERSON and LOUIS H. NOLTE, citizens of the United States of America, and residents of Cincinnati, county of Hamilton, State of Ohio, have invented certain new and useful Improvements in Reinforced Concrete Flooring, of which the following is a specification.

The object of our invention is a concrete flooring, which is reinforced in a uniform degree, above its supporting beams, so as to resist the tensile stresses which are developed there in the upper strata of the flooring, by loads located simultaneously upon opposite sides of the beam.

The invention will be described first in connection with the accompanying drawings and then will be particularly pointed out in the claims.

In the drawings, Figure 1 is a perspective view of a portion of flooring embodying our invention, in the process of construction. Fig. 2 is a transverse sectional view of a flooring embodying our invention. Fig. 3 is a diagrammatical view, for illustrating the strains which are developed in the flooring by loads located upon opposite sides of a beam.

Referring to Fig. 1: A, indicates the temporary frame-work, for molding the concrete, the channels, a, indicating the molds for the beams. Upon the frame work straddling the channels, a, a series of metal brackets, B, are placed at regular intervals, to carry a longitudinal supporting rod, C, centrally above each channel. Longitudinal rods, D, are placed upon the frame-work between the channels, in the usual manner. Straight transverse rods, E, are then laid upon the longitudinal rods, D. Alternating with the transverse rods, E, transverse rods, F, are placed upon the longitudinal rods, D. Rods, F, have arcs, f, formed in them which pass over and rest upon the supporting rods, C, which holds the arcs, f, at a uniform distance above the frame work, A.

Referring to Fig. 2: The usual longitudinal rods, G, having been placed in the chan-

nels, a, concrete, H, is filled in upon the frame, A, to the desired depth.

Referring to Fig. 3: When loads are placed upon the flooring at the points, 2, 2, upon opposite sides of the beam there are tensile stresses developed in the upper strata of the flooring above the beam, 3, as indicated by the separating arrows and compressive stresses in the lower strata, as indicated by the approaching arrows. To take up the tensile stresses it is necessary to have a metal member. The compressive stresses in the lower strata are resisted well by the concrete itself. The points at which these tensile stresses will be developed most strongly will vary with the distance apart of the beams, the weight of the loads to which the flooring is subjected and the depth of the flooring.

I have illustrated as the preferred form of bracket, B, one with divergent legs, b, b', and a horizontal member, b², since this bracket is one whose height may be readily diminished by a blow upon the member, b², thereby giving a greater spread to the legs, b, b', in order to regulate the height at which the supporting rod, C, is held above the frame, A, to meet the conditions to which it is presumed the floor will be subjected.

What we claim is:

1. A concrete construction consisting of concrete beams reinforced with longitudinal metal rods and a concrete flooring supported by the beams in combination with brackets with divergent legs straddling the beams, supporting rods located upon the brackets, rods located transversely to the supporting rods and having upwardly curved arcs formed therein to rest upon the supporting rods.

2. A concrete construction consisting of concrete beams reinforced with longitudinal metal rods and a concrete flooring supported by the beams in combination with brackets located in the concrete and straddling the beams, supporting rods located upon the brackets and rods transverse to the supporting

rods, one set of said rods being straight and passing beneath the supporting rods and the other set alternating with the said set and having arcs curved upward and resting upon 5 the supporting rods.

3. A flooring to be molded in position consisting of a flat frame-work with longitudinal channels for molding the beams, brackets straddling the channels at intervals, support-

ing rods carried by the brackets and rods 10 transverse to the brackets and having up-curved arcs to engage the supporting rods.

WILLIAM P. ANDERSON.
LOUIS H. NOLTE.
